UNITED STATES PATENT OFFICE.

JOHN McC. WATSON, OF PITTSBURG, PENNSYLVANIA.

DESIGN FOR A CASTER-BOTTLE.

SPECIFICATION forming part of Design No. 12,791, dated February 21, 1882.

Application filed January 18, 1882. Term of patent 3½ years.

To all whom it may concern:

Be it known that I, JOHN McC. WATSON, of Pittsburgh, in the county of Allegheny and State of Pennsylvania, have invented a new and useful Improvement in Designs for Caster-Bottles; and I do hereby declare the following to be a full, clear, and exact description thereof, reference being had to the accompanying drawings, forming a part of this specification, in which—

Figure 1 is a side elevation, and Fig. 2 a vertical section, of a caster-bottle made after my improved design.

Like letters of reference indicate like parts in each.

I form the lower part of the bottle—preferably the lower three-fifths of its length—of a pear-shaped bulb form, *a*, with a flat bottom, *b*. The upper part of said bulb merges into a ring, *c*, which is preferably at about three-

fifths of the height of the bottle. From the ring *c* to the shoulder *d* the sides are concave, as at *e*, and on the top of the shoulder is the mouth *f*, which is either of screw form for the application of a screw-cap, *g*, or of lip form for the reception of a stopper, *h*.

I propose to apply this design to caster-bottles generally, and also to other articles of table-ware not used in a caster-stand.

My design is plain and handsome.

What I claim as my invention, and desire to secure by Letters Patent, is—

The design for caster-bottles, substantially as described and shown.

In testimony whereof I have hereunto set my hand this 13th day of January, A. D. 1882.

JOHN McC. WATSON.
